Primary Examiner — Michelle E. Wilson*Assistant Examiner* — Caitlin A Laverty(74) *Attorney, Agent, or Firm* — Richard Elliott Halsey(57) **CLAIM**

The ornamental design for an attachable case for sunglasses, as shown and described.

DESCRIPTION

FIG. 1 is a front view of the case for sunglasses showing my new design;

FIG. 2 is a rear view of the attachable case for sunglasses;

FIG. 3 is a side view of the attachable case for sunglasses;

FIG. 4 is a side view of the attachable case for sunglasses;

FIG. 5 is a top view of the attachable case for sunglasses;

FIG. 6 is a bottom view of the attachable case for sunglasses; and,

FIG. 7 is a front view in perspective of the attachable case for sunglasses.

The broken lines showing the sunglasses and clip of FIG. 1 show the environment of the attachable case for sunglasses that form no part of the claimed design. The front surface is transparent.
